PLAY SHELTER

Harold R. Goodale, Bristol, Conn.

Application May 6, 1937, Serial No. 141,181

6 Claims. (Cl. 135—1)

The following description relates to an invention in play shelters as illustrated on the accompanying drawing. Small children like to make use of miniature play houses, shelters, tents or the like which they may enter themselves and use for the placement of dolls, toys or other play equipment. Many play structures of this nature require extended space for installation or storage and are not well adapted for the restricted living quarters now in vogue. My invention is developed around the use of a collapsible framework and specifically the square topped collapsible card table now in extended use. As these square tables are of general household utility and universally available, they render themselves readily to temporary use as part of play equipment. The play shelter using such a foundation or framework may then be given a satisfactory substantial appearance simulating an actual dwelling, canopy or tent by the use of a few simple parts.

It is an object of my invention to produce a play shelter simulating an actual shelter such as a miniature house or tent with a minimum of equipment and material.

It is a further object of my invention to provide such a structure in a form which may be folded and stored in a compact receptacle which itself is made use of in the assembly of the shelter.

An additional object of my invention is to provide facilities by which the skeleton or framework of the structure can be built up using the ordinary collapsible card table as a foundation or base. In this manner the final structure may vary from the proportions of the table either by additional height or extension of the ground plan.

Other objects of the invention will be readily understood from the following description of a preferred form supplemented by the accompanying illustrations in which

Fig. 1 is a perspective view of the housing as assembled to simulate the two story dwelling;

Fig. 2 is an expanded perspective view of the receptacle and cover used in the assembly of the shelter and alternatively to house the material for storage;

Fig. 3 is a schematic side elevation showing the opening in one side wall of the shelter;

Fig. 4 is a perspective view of the skeleton or framework comprised by a conventional card table and supplementary extensions for the legs;

Fig. 5 is a modified form of the shelter simulating a pyramidal tent;

Fig. 6 is an enlarged side elevation of the extension means shown in Fig. 4;

Fig. 7 is a front elevation of the same and

Fig. 8 is a modified form of the support for the apex of the shelter. 5

As illustrated the novel play shelter simulates one or another form of housing structure and may either appear as a complete dwelling or as a temporary canopy or tent. The device is made of light canvas or similar fabric and may be decorated to carry out the resemblance to a building structure. Consistent with this the central support for the apex of the shelter may be made in the form of a chimney as shown. The canvas or other fabric is stitched along its seams in the desired shapes and give reinforcement for example, along the roof line where the shelter is principally supported. 10

In the form shown in Fig. 1 the sides 11 are vertical and decorated to resemble the side walls 20 of a dwelling house. These side walls may have openings such as windows or doors. To allow a child to enter the house one side wall is slit vertically as shown at 12 so that the flaps 13, 13 may be turned back to afford entrance. The 25 pyramidal roof 14 is also made of like fabric and stitched at its lower edges to the top edges 11 thus forming a reinforcement along the roof line where the structure rests upon its support. 30

The support for the shelter consists of the well known collapsible card table 15 having a square top 16 and foldable legs 17.

In some instances the top 16 is not high enough to permit a child to walk under it and accordingly the side walls 11 may be lengthened 35 a suitable distance. In such case the legs 17 of the table are mounted in U-shaped extensions 18 the upper portions of which are clamped on the legs 17 by means of bolts 19.

The pyramidal roof 14 is supported in dis tended position above the table top 16 by means of a member 20. This member is a hollow rectangular prism which forms a receptacle or box 40 to hold the cloth shelter during transport or storage. The box 20 has a cover 21 fitting over the 45 top. This cover has inwardly sloping shoulders 22 which conform to the pyramidal shape of the roof 14 and coincide with the apex of the latter. A vertical extension 23 on the top 21 projects through the square opening at the apex of the roof and gives the appearance of a chimney for the housing. 50

When it is desired to store the shelter the fabric parts 11 and 14 are lifted off of the table and cover 21. They can then be folded compactly 55

and placed within the box 20 along with the extensions 18 and other incidental parts. The covered box is then a secure and satisfactory means for keeping the shelter in good condition.

5 Where it is unnecessary to provide storage for the device, the box 20 may be replaced by a pedestal support such as shown at 24 in Fig. 8. This has a base 25 and a top 26 the latter simulating the chimney of a house. Any suitable 10 means may be used for attaching the apex of the roof 14 to the chimney 26.

15 The invention may also take the form of a pyramidal canopy or tent such as is illustrated in Fig. 5. Here the same table 16 and its collapsible legs 17 are used to support the tent at its roof line. Box 20 rests upon the top of the table in a manner already described and has a cover 28 supporting the apex of the tent. In 20 this instance the cover is either pyramidal or some stiffening means is inserted in the apex of the roof to maintain the desired peak.

25 In either event the roof 14 is continued up to this peak.

25 The side walls 29 are allowed to flare outwardly of the base to give greater space within the tent. As it is intended that the shelter be used indoors where convenient means are lacking for holding the lower edges of the side walls stretched, separate means are provided. At each corner of 30 the lower edges of the tent a strut 30 is sewed in such position as to extend radially toward the center of the tent. At the inner free end of each strut, attaching means are provided to hold the legs of the table. In this way the table provides 35 means not only for supporting the tent but also for stretching the lower edges and holding the side walls in proper position.

30 A roll door 31 is provided in one side of the tent as shown.

40 In the above description I have pointed out the preferred embodiment of this invention without, however, limiting myself in minor details and proportions beyond what is indicated by the following claims.

45 What I claim is:—

1. A play tent comprising a regulation card table in combination with a one-piece fabric shelter enclosing the table and having connected side walls, the upper edges of the side walls substantially conforming to and being supported by the 5 edges of the table.

2. A play tent comprising a supporting card table in combination with a fabric shelter fitting over the table and having connected side walls with a sloping roof spaced from the table, the 10 upper edges of the side walls substantially conforming to the edges of the table, and a supporting member interposed between the table top and the sloping roof.

3. A play tent comprising a supporting table 15 in combination with a fabric shelter fitting over the table and having connected side walls with a sloping roof spaced from the table, a supporting member interposed between the table top and the roof, the supporting member having a portion 20 simulating a chimney and projecting through a hole in the roof.

4. A play tent comprising a supporting table in combination with a fabric shelter fitting over the table and having connected side walls with 25 a sloping roof spaced from the table, a supporting member interposed between the table top and the sloping roof, said supporting member comprising a hollow box of a capacity to contain the shelter when the latter is folded. 30

5. In a device of the character described, a play tent comprising a fabric shelter having a sloping roof with an opening, and a roof supporting member having a portion simulating a chimney and adapted to project through the opening, the member being formed as a hollow box of a capacity to contain the shelter when the latter is folded. 35

6. A foldable fabric play tent and a hollow support therefor, the support having a portion 40 simulating a chimney and adapted to project through an opening in the tent, the support being formed as a covered shipping box of a capacity to contain the tent when the latter is folded.

HAROLD R. GOODALE. 45
